UNITED STATES PATENT OFFICE.

HENRY W. SUMNER, OF SEATTLE, WASHINGTON.

OIL-FEED PUMP FOR INTERNAL-COMBUSTION ENGINES.

1,338,338.

Specification of Letters Patent. Patented Apr. 27, 1920.

Application filed July 3, 1918. Serial No. 243,215.

To all whom it may concern:

Be it known that I, HENRY W. SUMNER, a citizen of the United States, and resident of the city of Seattle, county of King, and 5 State of Washington, have invented certain new and useful Improvements in Oil-Fee Pumps for Internal-Combustion Engines, of which the following is a specification.

My invention relates to pumps used for 10 supplying fuel oil to internal combustion engines and consists of improvements there- in designed to make them more efficient and reliable and to facilitate keeping them in good shape. It also comprises an attach- 15 ment whereby a visible indication is promptly given of the occurrence of any ob- struction in the pump which tends to inter- fere with its operation and delivery of the proper amount of oil.

20 The objects of my invention may be de- termined by an inspection of the specifica- tion and the claims thereof.

The particular features of my invention which I consider to be new and upon which 25 I desire a patent will be described in the following specification and set out in de- tail in the claims.

In the drawings, I have shown my inven- 30 tion in a type of construction which I now prefer, although aware that many of the details might be changed without, how- ever, changing the principles employed.

Figure 1 is a side view or elevation of a 35 pump having my invention incorporated therein and the means for operating said pump, a portion of the pump actuating mechanism being shown in section.

Fig. 2 is a longitudinal section through 40 the pump proper, that is, the cylinder with the valve mechanism.

One of the objects sought in producing this pump is a mechanism wherein the parts which constitute the wearing members, may be made so that they are easily removable 45 and also easily renewable, and of such character of construction that their manufacture consists of simple operations which may be cheaply performed. Another object is also to provide a pump of such design that valves 50 may be largely eliminated, thus contributing to simplicity and efficiency.

The pump is of that type known as a 55 plunger pump. The plunger 1 is a plain cylinder. This enters a casing 2, which cas- ing is bored, said bore being in two sections of different diameters. The lower section

20, is a bore of a diameter to fit the plunger 1, the other section 21 is of a larger diameter. The plunger is intended to fit closely in the smaller section 20 of the bore, although this 60 fit is hardly intended to be of such character as to be relied upon solely to prevent escape of the oil.

The outer portion, or main body, 10, of the plunger, has secured thereto, an inner 65 end section 12, which latter is the operating member of the plunger and this is made a close, accurate fit within the casing and in the sleeve 3 which is placed in the larger portion of the bore of the casing. This re- 70 movable head 12, is made of hardened metal and of as accurate a fit as it is feasible to make and secure free reciprocative move- 75 ment. It is removable and secured to the body 10 of the plunger, so that, when de- sired, it may be removed and another head substituted therefor.

A convenient manner of doing this is that illustrated in Fig. 2. The head 12 is pro- 80 vided with a T-shaped flange which fits a corresponding groove formed in the body 10 of the plunger. These two parts are readily removed by relative transverse movement, but are securely locked together and held in alinement while in working posi- 85 tion in the pump.

The sleeve 3 which fits in the inner or bot- 90 tom end of the larger portion 21 of the bore in the casing, has an external peripheral groove 30, which is connected with the cen- tral bore of the sleeve through ports 31. The casing 2 is provided with a port or 95 opening, 22, for connection therewith of the oil supply pipe. This is positioned so as to register with the peripheral groove 30 in the sleeve 3.

The reciprocation of the head 12 of the plunger, is of such extent that, in its lower- 100 most position, it uncovers the port 31 and its uppermost position travels well beyond these, the extent of this travel beyond the port determining the amount of fuel which is delivered at each stroke. It is seen that the plunger forms its own valve.

Locked above the sleeve 3, within the cas- 105 ing, is a valve containing sleeve 4. This sleeve is centrally bored, forming a cylin- der for the reception of the valve sleeve 44. At its lower end, this bore is reduced in diameter and forms a discharge port 41, 110 through which the oil is forced by the plun- ger. Surrounding this, is a valve seat 40.

Just above the valve seat 40 is an exteriorly recessed peripheral groove 42; that is, this groove is in the wall of the sleeve, and extends outward from the bore within which the valve fits.

The valve 44 is a thin shell or cylinder, having its lower end closed and shaped to accurately fit the valve seat 40. Just above this lower end or valve head, it has ports 10 43, which register with the groove 42. The sleeve 4 is held downward against the adjacent end of the cylinder sleeve 3, in any suitable manner. The means illustrated and which I prefer to use, is a sleeve 5 which 15 has a head 50 engaging the upper end of the sleeve 4.

The stem of this sleeve 5 is surrounded by a sleeve 51 which is threaded into the upper end of the casing 2, thus forming a 20 nut, the lower end of which bears upon the upper shouldered surface of the head 50, so that the latter may be powerfully forced downward or into the casing and against the valve sleeve 4 and the latter against the 25 cylinder sleeve 3. It is thus possible to make a tight joint between the head 50 and the upper end of the sleeve 4 while the lower end of the sleeve 4 may directly contact with the upper end of the sleeve 3.

30 I prefer, in order to insure a tight joint, to use a packing ring 52, which is placed between slightly coned surfaces on the ends of the two sleeves 3 and 4. This ring may be of copper or other relatively soft metal. 35 It will thus compress or flow a sufficient amount to insure tightness in the joint between the two sleeves and also a tight joint against the surfaces of the casing. The whole device is thus made absolutely secure 40 against leakage.

The valve 44 is normally held down upon its seat by a spring 45 which, at its upper end, bears against the lower end of the sleeve 5. Within the central bore of the 45 sleeve 5 is a pipe 53 which forms the pipe for the discharge of the oil. This pipe may be brazed or otherwise securely held in the sleeve 5 and leakage between the pipe and the sleeve thus prevented. At the lower end 50 of the casing, I have provided a gland or stuffing box 13, which may be employed as an additional means for securing against leakage of the oil about the plunger. This may be of any usual or suitable construction.

55 The means which I prefer to employ for operating the plunger is shown in Fig. 1. The lower end of the plunger 1, is screw threaded into a sleeve 6. This sleeve has 60 sliding and guiding engagement within a bore formed in a member 60 of the frame or of a member which is secured to the frame. The sleeve has a stem 61, extending downward and through a hole formed 65 in the cross head or slide block 7, the latter

being guided in suitable members carried by the frame. The bolt 61 is loose in the block 7 to the extent that relative reciprocation between the two is freely possible. At its lower end the bolt 61 is provided with a nut 62 which limits upward movement of the bolt relative to the sliding block 7.

70 At the upper end of the block 7 is a washer 70, which is provided, on its upper surface, with suitable seats for two coiled springs 71 and 72. The outer spring 71, at its upper end, bears against a member of the frame or a member which is fixedly secured upon the frame. The function of this 75 spring is to secure the downward or return movement of the block 7 and also of the pump plunger which is connected therewith. For convenience in adjusting the initial tension placed upon this spring, I have provided a threaded sleeve 73, which acts as the 80 direct support for the washer 70. This sleeve 73 is threaded into a member carried by the frame so that it may be adjusted vertically, thereby making it possible to vary 85 the initial tension of the spring 71.

90 The inner spring 72, acts in compression between the washer 70 and the head 6 and constitutes the member through which the effort required to actuate the plunger under 95 normal conditions without being compressed, and yet be capable of giving, in case any obstruction enters the pump, is lessened thereby preventing a possibility of over straining or breaking the pump or its operating parts.

95 In case of obstruction of this sort, the extent of stroke of the pump plunger will be reduced. In order to give visible warning of this, I have provided what I call a tell-tale, the same consisting of a small wire or 100 rod 8, which is secured at one end to washer 70 and therefore has a movement which corresponds exactly with that of the reciprocating head, 7. At its upper end its tip 80 is 105 placed adjacent to and in exact relation with some part of the plunger or a part connected to or moving in correspondence therewith. As shown, it is in exact registry with the shoulder of the head 6. If, during 110 the operation of the pump, relative movement between this tell-tale finger and the plunger is observed, it is known at once that there is some obstruction which prevents 115 full operation of the plunger. The pump 120 may then be taken apart, investigated, and cleaned.

125 I have shown the reciprocating head 7 as being secured to a lever 9, to which it is pivoted at 90. This lever operates upon a 92 movable fulcrum carried by an arm 92 which is capable of a swinging movement about its pivot axis 93. The lever 9 has a cam roller or tappet 94, which is engaged by a cam 95 carried by a rotating shaft 96, 130

the latter being turned in any suitable manner from the engine shaft. The means employed for reciprocating the head 7 are, however, no part of this present invention. 5 Any suitable means for reciprocating the same may be employed.

It is believed that the operation of the device is evident from the above description and drawings. The oil supply flows freely 10 to the groove 30 in the pump and the plunger acts after the manner of an ordinary plunger to force the oil through the ports 41, 42, and 43, and thence through delivery pipe 53.

15 In order to clean the pump, it is only necessary to remove the nut 51 and it is then possible to take out all the sleeves contained within the casing, clean them, replace them or insert substitutes. It is thus possible 20 to quickly correct any operating trouble in the pump. All the parts of this pump are of such character that they may be cheaply and accurately made and parts may be kept on hand for replacing those which 25 may not be giving satisfaction.

What I claim as my invention is:

1. In an oil feed pump for internal combustion engines, a plunger body and a plunger head of like diameter, said head being 30 removably secured to the body, and a cylinder casing having a bore in which the plunger is reciprocable, said bore being of a size to fit closely about the plunger throughout the path of travel of the joint 35 between the head and body.

2. In an oil feed pump for internal combustion engines, a plunger body and a plunger head of like diameter, said head being secured to the body to resist axial separation 40 and freely removable therefrom by relative movement transversely of their axis, and a cylinder casing having a bore in which the plunger is reciprocable, said bore being of a size to fit closely about the plunger 45 throughout the path of travel of the joint between the head and body.

3. An oil feed pump for internal combustion engines having a plunger body and a plunger head both of like diameter, one 50 of said members having a transversely extending tongue in its end and the other member having a transversely extending groove in its adjacent end fitting about the tongue in the first member, and adapted to 55 prevent relative axial movement therebetween.

4. In an oil feed pump for internal combustion engines a casing having an oil supply port, a cylinder sleeve fitting said casing and removably secured therein, said sleeve having a peripheral groove communicating with said port, and ports extending from said groove to the central bore, and a plunger fitting said bore of the sleeve.

5. In an oil feed pump for internal com-

bustion engines, a casing having a cylindrical bore and an oil admission port, a cylinder sleeve fitting said bore and provided with a peripheral groove registering with said port and ports connecting said groove 70 with its central bore, a plunger fitting said sleeve, and a valve sleeve also fitting the same bore in the casing and engaging the end of the cylinder sleeve and having a central discharge bore, and a valve in said bore. 75

6. In an oil feed pump for internal combustion engines, a casing having a cylindrical bore, in two parts of different diameters, a plunger fitting the smaller part of said bore and extending into the larger part, 80 a cylinder sleeve fitting the larger part of said bore and the plunger and having an exterior peripheral groove and ports connecting this groove with its bore, a valve sleeve fitting the casing and holding down the cylinder sleeve, a valve in said latter sleeve and a discharge pipe communicating with the bore of the valve sleeve. 85

7. In an oil feed pump for internal combustion engines, a cylinder, a plunger fitting 90 said cylinder, a sleeve fitting the cylinder and having a valve seat within its bore, and an outwardly recessed groove just within the valve seat, a valve having a tubular body fitting the bore in said sleeve and ports registering with the recessed groove of the sleeve. 95

8. In an oil feed pump for internal combustion engines, a cylinder, a plunger fitting 100 said cylinder, a sleeve fitting the cylinder and having a valve seat within its bore, and an outwardly recessed groove just within the valve seat, a valve having a tubular body fitting the bore in said sleeve and ports registering with the recessed groove of the 105 sleeve, a plug closing the cylinder and engaging the valve-containing sleeve and having an oil discharge passage therein, and a spring engaging said plug and the valve to normally hold the valve seated. 110

9. In a fuel feed pump for internal combustion engines, a plunger mechanism having two parts, one connected with the actuating means for positive movement and a spring connecting this part with the other, 115 and a tell-tale finger connected with one of these parts and extending to a position adjacent the other part.

10. In a fuel feed pump for internal combustion engines, a plunger actuating means comprising two parts connected to move together, one of said parts being positively connected with the plunger actuating mechanism and the other with the plunger, a spring forming the actuating connection between said two parts, and a tell-tale finger actuated by one of said parts and having an end adjacent to the other part. 125

11. In a fuel feeding pump for internal combustion engines, a plunger actuating 130

mechanism having two parts mounted to reciprocate along a common axis, one of said parts having a positive actuating connection with the pump actuating means and the other having a positive connection with the plunger, a bolt connecting said parts and limiting their separation, a spring forming the plunger driving connection between said parts, and a tell-tale finger carried by one of said parts and extending adjacent to the other part.

12. In a fuel feed pump for internal combustion engines, a plunger mechanism having two parts, one positively connected with the actuating means and the other with the 15 plunger, a spring acting to hold apart said parts, and means for limiting the separation of said parts.

Signed at Seattle, Washington, this 25th day of June, 1918.

HENRY W. SUMNER.
